UNITED STATES PATENT OFFICE.

FRANK DE MINICO, OF NEW YORK, N. Y., ASSIGNOR TO POLLARD-ALLING MANUFACTURING COMPANY, OF NEW YORK, N. Y., A CORPORATION OF NEW YORK.

PRINTING PLATE.

Application filed August 30, 1922. Serial No. 585,128.

To all whom it may concern:

Be it known that I, FRANK DE MINICO, a citizen of the United States, and a resident of New York, borough of Bronx, in the 5 county of Bronx and State of New York, have invented certain new and useful Improvements in Printing Plates, of which the following is a specification.

This invention relates to printing plates 10 and particularly to such plates as are made of thin sheet metal adapted for having embossed thereon letters or symbols, and which are provided with means for articulation into a continuous chain. The object of my 15 improvements is to provide a printing plate of the character specified, simple in construction, durable in use and having interlocking features of security and ease of assemblage for articulation with others of its 20 kind.

With these ends in view my improvements comprise features illustrated in their preferred embodiment in the drawing accompanying this specification wherein Figure 1 25 is a perspective view of my improved printing plate. Fig. 2 is a section on line 2—2 of Fig. 1. Fig. 3 is a perspective view similar to that of Fig. 1 and showing some features of modification. Fig. 4 is a section on 30 line 4—4 of Fig. 3. Fig. 5 is a perspective view similar to those of Figures 1 and 3 and showing further modifications. Fig. 6 is a section on line 6—6 of Fig. 5. Fig. 7 is a perspective view showing the assemblage of two plates such as that shown in 35 Fig. 1. Fig. 8 is a similar view to that of Fig. 7 showing the assembling of two plates such as that shown in Fig. 3. Fig. 9 is a view similar to those of Figs. 7 and 8 showing 40 the assembling of two plates such as that shown in Fig. 5. Fig. 10 is a section on line 10—10 of Fig. 6. Fig. 11 is a fragmentary section on line 2—2 of Fig. 1 but showing a portion of a second plate in articulated relation therewith.

Plates of this general character may be found illustrated and described in U. S. Patent No. 866,863 to Hopkins, granted Sept. 24, 1907 and in U. S. Patent No. 50 866,928 of Sept. 24, 1907 to Grieser. The present invention is in the nature of improvements in the plates shown in said patents. My improvements are particularly directed to the hinge portions of such plates 55 with a view to add strength thereto, to in-

crease the ease with which the plates may be assembled into an articulated chain and separated from one another when occasion requires. Other features will appear later herein.

In the very nature of plates of the character of those specified, it is necessary that thin and rather soft metal be employed so that the lettering or symbols may be embossed readily thereon. Heretofore it has 60 been convenient and customary to make the pintles which form one member of the hinge, of the same thickness as the body of the plate. This necessarily resulted in a rather frail pindle which was liable to be 65 bent or broken off in use. The present invention is directed among other objects to providing strong pintles, by making them 70 of a double thickness of metal.

Directing attention now more particularly 75 to the drawing, in Fig. 1 thereof, body 3 of the plate preferably has on one lengthwise edge a narrow upstanding strengthening flange 5, from which project in substantial parallelism with the body of the plate one 80 or more outstanding ears, as 7. Said ear comprises pindle portion 9 which is joined to said plate body 3, or its flange 5, by a relatively short neck 8, which allows said pindle portion to project in both directions 85 lengthwise said plate, beyond said neck, thereby providing pintles 9^a and 9^b. For strengthening said pindle portion the body thereof is folded over on itself, whereby a double thickness of metal is provided pref- 90 erably throughout its length. Very strong pintles 9^a and 9^b are thus provided, which will stand indefinite interlocking with their coacting hinge members without bending or 95 breaking.

On that edge of said plate opposite said pindle members, and in parallelism therewith the metal of the plate is rolled over to bring the edge of the plate preferably close to or into contact with the body of the plate, 100 thus forming a hollow approximately cylindrical rib 10. At that portion of said rib opposite pindle member 7 said rib is cut away at 11 to provide an opening for the entry of said pindle member. The major portion of said opening between the adjacent ends of rib portions 10^a and 10^b is slightly longer than the length of neck 8 and, for admitting pindle 9^a within the cylindrical opening in rib portion 10^a, said rolled over portion is 105 110

notched out at that edge thereof adjacent the body of the plate and adjacent opening 11. This forms a gateway 12 for the entrance of pintle 9^a. That end of cylindrical rib portion 10^b facing opening 11 is similarly notched at 13 for admitting pintle 9^b. For similarly admitting the other pintle member, opening 11^c opposite thereto is provided and the adjacent ends of rib members 10^b 10 and 10^c are notched similarly to the adjacent ends of rib members 10^a and 10^b.

Two plates of the character described may be hinged together as shown in Fig. 7 wherein the plates are laid face to face with their ends in the same planes respectively and with the pintle members of one facing the openings between the rib members of the other. The pintles will there be seen entering the notches respectively in the rib members 20 and after being pushed therethrough into the hollow portion of the rib members, the front edge of the upper plate may be lifted and the plate rotated on its pintles in interlocking relation with the under plate.

Heretofore it has been customary in rolling over the edge of the plate to provide seats for the pintles, to leave a lengthwise space between the rolled over edge of the sheet and the body of the sheet for the entry of said pintles into engaging position with the interior of the rib portions. The practice set forth in the present application is an improvement over that earlier practice in that as the plate edge is rolled over into contact with the body of the plate the cylindrical formation can be attained with greater accuracy and uniformity from one plate to another, than if a material space is left 35 between said edge and body. Variation in thickness of metal and in the hardness thereof contribute to variable results in rolling over if the edge of the plate is not forced against the body.

40 In the modification of Figures 3 and 4 notch 12 of Fig. 1 has been omitted, which results in a different mode of assembling two plates, and which mode will be described presently herein. A further feature of difference between the plate of Fig. 3 and that of Fig. 1 lies in the form of the neck which connects body 3 of the plate or flange 5 thereof, with pintle portion 9. In said modification neck 8 has a lengthwise rib formed 45 therein, in cross section, see Fig. 4, preferably of U shape and preferably the U is reversed. The object of this rib is to shorten the distance between flange 5 and said pintle portion, thereby closing up to some extent the space between the pintles 9^a, 9^b and said flange 5. The object of said closing up 50 will be understood by reference to Fig. 11, wherein is shown the pintle portion of the plate of Figures 1 and 2 interlocked with the rib edge of a similar plate. Therein plate a

has been pushed toward and over plate b, whereby the pintle portion 9 projects outwardly to the right from notch 13. This prevents plate a from folding downwardly farther than shown. In some cases further 70 folding down is desirable and which folding down may be accomplished by withdrawing plate a slightly to the left, when the pintles will engage the inside of the cylindrical rib and permit such further folding. By closing up the space between the pintles and rib 5 as shown in Figures 3 and 4 the tendency of the pintle portion to misplacement such as shown in Figure 11 is overcome.

80 It will be obvious to those skilled in the art that this general result might be accomplished by increasing the diameter of rib 10 or by punching a narrower opening between flange 5 and pintles 9^a and 9^b. The first of these is objectionable in that it would prevent the interchange of such a plate with those now in use which amount to many millions. The second of these is objectionable because the cutting blade of a punch 90 to punch out so small a space as that between the flange and pintle of the plate of Figures 3 and 4 would be so frail as to be highly liable to destruction in making these plates in quantity, while the punch for the space between the flange and pintle of the plate of Figures 1 and 2 is much thicker and stronger and is serviceable for quantity production.

95 Referring now to Figure 8 the method of assembling two plates such as shown in the modification of Figures 3 and 4 is there illustrated. Therein the upper plate is skewed slightly relatively to the lower plate and pintle 9^a is slid endwise to the left into the inner end of hollow cylindrical rib 10^a; then 105 the right hand portion of the upper plate is swung into parallelism with the lower plate, when the other pintles will pass through the respective notches of the rib portions and interlock within said rib portions. This 110 modification is in some cases preferable to the showing of Figs. 1 and 2 in that plates of this modified form cannot be separated by withdrawal in parallelism as with said plates of Figs. 1 and 2, as shown in Fig. 7. 115

120 In the modification of Figures 5 and 6 the notch is omitted from rib portion 10^a and the notches in rib portions 10^b and 10^c are about twice as long as those in the plates of Figures 1 and 3. That is those notches 125 are each slightly more than the combined length of two pintles. In accordance with this modification two plates are assembled by placing the upper plate slightly offset to the right, on the lower plate, so that not only the pintle as 9^a but an equal length therewith of the pintle body portion 9 enter the corresponding notch as 14, Fig. 9. This permits the opposite pintles respectively to pass by those ends of the rib portions which 130

have no notches. Then when said pinte portions have been fully entered, into line with the interior of said rib portions, the upper plate is slid endwise to the left where-
5 by the left hand pintles respectively enter their corresponding rib portions of the under plate. The free edge of the upper plate is then raised and the plate folded over into the plane of the lower plate thus completing
10 the assembly.

In some cases in assembling and disassembling the plates there is a tendency for the pintles, as 9^d, when in line with the interior of the rib portions, to slide endwise, Figure 15 9, whereby the opening up of the top plate is prevented by the upper wall of the notch, as 14, engaging neck 8. To prevent this I provide a stop against such endwise move-
20 ment. A convenient device to this end com-
prises a lip 15 turned inwardly from the lower edge portion of the rib, as 10^c, Figures 1, 5, 6 and 10. This turned-in portion can be conveniently formed of that portion of the corner of the rolled over portion
25 which would otherwise be cut away to form notch 14.

I claim:

1. In a printing plate of sheet metal adapted for articulation with others of its kind the combination of a body having on one edge thereof an outstanding ear comprising a pinte portion and a neck portion, said pinte portion including opposite pintles projecting in opposite directions beyond
30 said neck portion and said neck portion having a lengthwise rib formed therein for bringing said pinte portion and said body closer together.

2. In a printing plate of sheet metal adapted for articulation with others of its kind the combination of a body having on one edge thereof an outstanding ear comprising a pinte portion and a neck portion, said pinte portion including opposite pintles projecting in opposite directions beyond
40 said neck portion and said pinte portion being formed of two thicknesses of said sheet metal.

3. In a printing plate of sheet metal adapted for articulation with others of its kind the combination of a body having on one edge thereof an outstanding ear comprising a pinte portion and a neck portion, said pinte portion including opposite pintles projecting in opposite directions beyond
50 said neck portion, said neck portion having a lengthwise rib formed therein for bringing said pinte portion and said body closer together and said pinte portion being formed of two thicknesses of said sheet metal.

4. In a printing plate of sheet metal adapted for articulation with others of its kind the combination of a body having on
60 one edge thereof an outstanding ear com-

prising a pinte portion and a neck portion, said pinte portion including opposite pintles projecting in opposite directions beyond said neck portion, said neck portion having a lengthwise rib formed therein for bringing
70 said pinte portion and said body closer together and said pinte portion being folded over upon itself whereby a double thickness
75 of metal is provided therein.

5. In a printing plate of sheet metal adapted for articulation with others of its kind the combination of a body having on one edge thereof an outstanding ear comprising a pinte portion and a neck portion, said pinte portion including opposite pintles projecting in opposite directions beyond
80 said neck portion, said body having formed on that edge thereof opposite said pinte portion and in parallelism therewith a plurality of rolled over hollow ribs, said ribs
85 being spaced apart a distance slightly greater than the length of said neck portion and one of said ribs having a notch in that end thereof facing the other rib and adjacent the body of the plate for the passage
90 therethrough of one of said pintles.

6. In a printing plate of sheet metal adapted for articulation with others of its kind the combination of a body having on one edge thereof an outstanding ear comprising a pinte portion and a neck portion, said pinte portion including opposite
95 pintles projecting in opposite directions beyond said neck portion, said body having formed on that edge thereof opposite said pinte portion and in parallelism therewith a plurality of rolled over hollow ribs, the edges of said rolled over rib portions lying
100 close to the body of the plate, said ribs being spaced apart a distance slightly greater than the length of said neck portion and one of said ribs having a notch in that end thereof facing the other rib and adjacent the body of the plate for the passage therethrough of one
105 of said pintles.

7. In a printing plate of sheet metal adapted for articulation with others of its kind the combination of a body having on one edge thereof an outstanding ear comprising a pinte portion and a neck portion, said pinte portion including opposite pintles projecting in opposite directions beyond said
115 neck portion, said body having formed on that edge thereof opposite said pinte portion and in parallelism therewith a plurality of rolled over hollow ribs, said ribs being spaced apart a distance slightly greater than the length of said neck portion, one of said ribs having a notch in that end thereof facing the other rib and adjacent the body of the plate for the passage therethrough of one of
120 said pintles and said notch having a length slightly greater than the combined length of said pintles.

8. In a printing plate of sheet metal adapt-

ed for articulation with others of its kind the combination of a body having on one edge thereof an outstanding ear comprising a pintle portion and a neck portion, said 5 pintle portion including opposite pintles projecting in opposite directions beyond said neck portion, said body having formed on that edge thereof opposite said pintle portion and in parallelism therewith a plurality of 10 rolled over hollow ribs, said ribs being spaced apart a distance slightly greater than the length of said neck portion, one of said ribs having a notch in that end thereof facing the other rib and adjacent the body of the 15 plate for the passage therethrough of one of said pintles and a stop therein adjacent its notch for limiting the endwise movement of the pintle therein.

9. In a printing plate of sheet metal adapted for articulation with others of its kind the combination of a body having on one edge thereof an outstanding ear comprising a pintle portion and a neck portion, said 20 pintle portion including opposite pintles 25 projecting in opposite directions beyond said neck portion, said body having formed on that edge thereof opposite said pintle portion and in parallelism therewith a plurality of rolled over hollow ribs, said ribs being spaced apart 30 a distance slightly greater than the length of said neck portion, one of said ribs having a notch in that end thereof facing the other rib and adjacent the body of the plate 35 for the passage therethrough of one of said pintles and a portion of the metal of said rib being turned inwardly at the base of said notch as a stop for limiting the endwise movement of the pintle in said rib.

10. In a printing plate of sheet metal adapted for articulation with others of its kind the combination of a body having on one edge thereof an outstanding ear comprising a pintle portion and a neck portion, said 40 pintle portion including opposite pintles 45 projecting in opposite directions beyond said neck portion, said body having formed on that edge thereof opposite said pintle portion and in parallelism therewith a plurality of rolled over hollow ribs, said ribs being spaced apart 50 a distance slightly greater than the length of said neck portion, and said ribs having notches in their infacing ends adjacent the body of the plate for the passage therethrough of said pintles respectively.

11. In a printing plate of sheet metal adapted for articulation with others of its kind the combination of a body having on one edge thereof an outstanding ear comprising a pintle portion and a neck portion, said 55 pintle portion including opposite pintles 60 projecting in opposite directions beyond said neck portion, said body having formed on that edge thereof opposite said pintle portion and in parallelism therewith a plurality 65 of rolled over hollow ribs, said ribs being spaced apart a distance slightly greater than the length of said neck portion, said ribs having notches in their infacing ends adjacent the body of the plate for the passage 70 therethrough of said pintles respectively and one of said ribs having a stop therein adjacent its notch for limiting the endwise movement of the pintle therein.

In witness whereof, I hereby affix my signature this 28th day of August, 1922.

FRANK DE MINICO.
